US0D1010639S

(12) **United States Design Patent** (10) **Patent No.:** **US D1,010,639 S**
(45) **Date of Patent:** **** Jan. 9, 2024**

(54) **NOTEBOOK COMPUTER**

(71) Applicants: **Po-Yang Chien**, Taipei (TW); **Hao-Jen Fang**, Taipei (TW); **Wei-Yi Chang**, Taipei (TW); **Chun-Chieh Chen**, Taipei (TW); **Chen-Cheng Wang**, Taipei (TW); **Chih-Wen Chiang**, Taipei (TW); **Sheng-Hung Lee**, Taipei (TW)

(72) Inventors: **Po-Yang Chien**, Taipei (TW); **Hao-Jen Fang**, Taipei (TW); **Wei-Yi Chang**, Taipei (TW); **Chun-Chieh Chen**, Taipei (TW); **Chen-Cheng Wang**, Taipei (TW); **Chih-Wen Chiang**, Taipei (TW); **Sheng-Hung Lee**, Taipei (TW)

(73) Assignee: **COMPAL ELECTRONICS, INC.**,
Taipei (TW)

(**) Term: **15 Years**

(21) Appl. No.: **29/767,599**

(22) Filed: **Jan. 24, 2021**

(30) **Foreign Application Priority Data**

Nov. 6, 2020 (TW) 109306165

(57) **CLAIM**

The ornamental design for a notebook computer, as shown and described.

DESCRIPTION

FIG. 1 is a perspective view of a notebook computer showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a notebook computer showing a second embodiment of our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The even-dash broken lines illustrate portions of the notebook computer that form no part of the claimed design. The

(Continued)

dot-dash broken lines define the bounds of the claimed design and form no part thereof. Unshaded surfaces form no part of the claimed design.

1 Claim, 8 Drawing Sheets
